X-RAY APPARATUS

Harry B. McEuen, Jacksonville, Fla.

Application February 15, 1930, Serial No. 428,798

14 Claims. (Cl. 250—34)

The invention is directed to an improvement in X-ray apparatus, wherein provision is made for overcoming known disadvantages of present apparatus of this type, and wherein, through certain details of construction and arrangement, the operative effect and efficiency of this type of apparatus is materially increased.

The operating energy for present-day X-ray apparatus is materially limited, owing primarily to the well-known fact that a very small proportion of such energy is converted into X-rays, while the remaining energy has been converted into heat for which no adequate dissipation has been provided. The focal spot area largely controls the energy limit, for under excessive current in the face of insufficient heat dissipation or diffusion, the tube is very liable to be damaged. The present type of tube proper, particularly the anode, is, as a result of its construction, the primary cause of a limitation in the operating energy of the apparatus, and is practically operative at such limited energy as to materially reduce the effectiveness of the apparatus as a whole.

The present invention has therefore for its primary object the production of an X-ray tube in which the anode is formed for a materially increased target or focal spot area, and in which the tube may be subjected to a continuous and effective heat dissipation under an operating energy far exceeding that possible with present type apparatus.

A further object of the invention is to so mount and support the tube as to avoid any limit to the natural expansion and contraction of the tube, with a view to avoiding the great liability of tube damage incident to the present means for tube support.

A further object is the provision of means for effective heat exchange with the anode for complete cooling purposes, together with means whereby the cooling medium is insulated from the high-potential energy and is maintained at ground potential.

A further object is the provision of an insulating medium circulated through the apparatus externally of the tube proper, and serving to completely insulate the parts of the apparatus, assist in cooling the parts, and prevent coronal discharge within the apparatus.

The invention in the preferred form of details is illustrated in the accompanying drawings, in which:—

Fig. 1 is a view in elevation, partly in section of the improved apparatus.

Fig. 2 is a section on line 2—2 of Fig. 1.

Fig. 3 is a sectional detail, showing the mounting of the anode end of the tube proper.

Fig. 4 is a section on line 4—4 of Fig. 1.

Fig. 5 is a sectional view of a detail, showing the mounting of one end of the tube proper.

Fig. 6 is a broken elevation, partly in section, of the anode and mounting in the tube proper.

The improved apparatus comprises what may be termed a casing 1, preferably constructed of one or more layers of metal in hollow cylindrical form, having an opening for the introduction of the various parts of the apparatus, with such opening hermetically sealed by a door 2.

Insulator posts 3 and 4 pass through the wall 15 of the casing, being fixed by means 5, each carrying a terminal current connector, as 6 and 7, externally of the casing, and each arranged internally of the casing to support the X-ray tube proper. The post 3 is provided with a central tube 8, connected with the connector 6, and forming a conduit for the leads 9 and 10 for the cathode circuit; the post 4 having a central rod 11 connected with the connector 7 for current passage, and also forming a support for the special carrier for the anode end of the X-ray tube.

The X-ray tube proper is, aside from the details hereinafter noted, of conventional form, as indicated at 12. The anode stem 13 is a hollow cylinder carrying a button 14, of tungsten or other suitable metal to provide the target or focal spot. The opposite end of the anode stem 13 extends beyond the end of the wall of the tube proper, the latter being of course sealed to the anode stem, and the extended end of the anode stem is closed, except for the cooling medium pipes. The end of the anode stem is formed as a rectangular extension 15, providing the supporting extension for the anode end of the X-ray tube. The opposite end of the X-ray tube proper carries the conventional type of cathode 16. The cathode end of the tube proper is formed as a threaded extension 17, to receive a cap 18, having a tubular extension 19, for supporting the cathode end of the tube.

A supporting section 20 of conducting material is carried, preferably through threaded connection, by the lower end of the conductor rod 11 of the post 4. This supporting section is formed with a transverse opening 21, in which the rectangular extension 15 of the anode end of the tube is slidably supported. A guiding support is given the extension by ball members 22, seating in openings formed in the walls of opening 21, and

having bearing contact on the anode-stem extension 15 through springs 23 tensioned by plates 24, secured to the external surfaces of the supporting section 20. A conductor 25, fixed in the extension 15, and to the section 20, together with the ball contacts 22 provide circuiting continuity.

The tube 8 in post 3 is terminally threaded to receive a right-angled support 26, the vertically depending portion of which is formed with an opening 27 to receive the extension 19 of the cap 18, a set screw 28 fixing the connection. The leads 9 and 10 of the cathode circuit pass through the extension 19 for the usual cathode energization.

15 The invention contemplates the cooling and insulation of the anode stem, and to this end provides for the circulation of a heat-exchange medium, which is subjected to a continuous cooling beyond the casing. The medium employed 20 is oil of high di-electric strength, and the means employed consists of insulating tubes 29 and 30 fixed in and opening beyond the casing 1, the lower ends of which tubes, arranged on a plane with the X-ray tube, are connected by flexible 25 couplings 31, with tube sections 32 and 33, respectively. The tube section 32, forming the inlet for the cooling medium, extends through the end of the anode stem 13, being sealed therein, and toward and terminating a short distance 30 from the target end of such stem. The tube section 33, forming the outlet of the cooling medium, is sealed in the closed end of the anode stem, being open, however, to the interior of the anode.

Beyond the casing 1, the cooling medium circu- 35 latory connections are arranged as pipes, flexible if desired, such as 34 and 35, are connected to and in open communication with the insulating tubes 29 and 30, respectively, the pipe 34 leading to and through a filter 36, having a pressure-regulating 40 by-pass 37, and beyond the filter, through a suitably driven pump 38, and to and through a coil 39 to which the pipe 35 is connected. The coil 39 is arranged in a cooling chamber 40, through which a cooling medium, as water, is controllably 45 circulated.

In addition to the cooling medium circulated through the anode of the X-ray tube, there is provision for cooling and insulation of the parts within the casing external to the X-ray tube 50 proper. The cooling medium here preferred is transformer oil of high di-electric strength, admitted to the casing 1 through pipe 41, opening through the lower portion of the casing, and exhausted from casing through pipe 42, open to the 55 casing at a point above the center of the casing.

The outlet pipe 42 leads through a coil 43 in a water cooled chamber 44, and from said coil through a filter 45 and a pump 46 to and through the inlet pipe 41. The cooling and insulating 60 medium controlled by this particular system is designed to completely fill the casing 1, and be continuously circulated, and incidentally cooled beyond such casing. In continued use of this medium more or less carbonization will occur, 65 lowering the insulating effect, but the external filtering removes such carbon particles and maintains the high insulating efficiency of the medium.

The heretofore proposed X-ray tubes operated in conventional holders, which have parts 70 at ground potential in the vicinity of the X-ray tube, or which have metallic parts within the high potential leads of the holders, tend to a certain coronal discharge, which not infrequently causes fracture or puncture of the X-ray tube. The 75 specific provision of the cooling medium above

described, coupled with the absence of metallic parts within the high potential field, and depending upon the complete immersion of the parts in a constantly-circulated, artificially-cooled medium, will maintain effective cooling, prevent 5 coronal discharge from the wall of the X-ray tube, or from other parts within the high voltage circuit, will insulate the walls of the X-ray tube from the wall of the casing, and will prevent breakdown incident to carbonization of the 10 medium.

The casing 1 is provided with the usual filter opening 47, for the exit of the X-rays, the filter of course providing a hermetic seal for the opening.

X-ray tubes, as previously known, when operated at voltages of two hundred kilo-volts, limit the milliamperage through the tube to fifty milliamperes for short intervals, and not over thirty milliamperes for longer periods of time. This 20 limits the filter thickness and the distance from the anode to the skin surface, preventing the use of thicker and denser filters desirable, for example, in X-ray therapy of cancer, particularly cancer at a depth below the skin surface, by 25 reason of length of time required. Furthermore, it is often desired to increase the target skin distance over the present limitation, in order to increase the depth dose as compared with the skin dose. Here again the time limit is the deciding 30 factor. With the present materially enlarged target area, the effective cooling of the anode stem, and of the external parts, provides an X-ray tube capable of much greater voltage application and milliamperage through the tube, without 35 the liability of tube damage. Thus the use of heavy or dense filters and increased target-skin distance is readily permissible without the time-limit handicap.

The anode stem 13 is a hollow cylinder having a 40 comparatively large diameter, and the cooling medium pipes are of such sectional area as will insure active and large heat-exchange with the cooling medium, that is the flow of such medium will be sufficient to greatly increase the heat 45 dissipation as compared with previous cooling effects for X-ray tubes. This also permits greatly increased energy capacity for the tube, and thus materially increases the efficiency of the tube for those effects previously possible only at practically prohibitive time expense.

What is claimed as new, is:—

1. An X-ray apparatus including a casing, an X-ray tube therein, conductor posts secured in the casing and supporting the tube, one end of the 5 tube being formed with a cylindrical hollow extension, an element carried by the post to receive the extension, means carried by the element for fixing the extension with respect to the element, said hollow extension forming a conduit for the conducting wires, the opposite end of the tube having a rectangular extension, a conducting element carried by the remaining post, said element being formed with an opening to receive the rectangular extension of the X-ray tube, and ball elements for guiding the extension and providing electrical continuity.

2. In an X-ray apparatus, a casing, an X-ray tube therein including an anode, an external source of dielectric oil, conduits intermediate said source and the interior of the anode, said conduits passing through the casing and delivering said oil immediately adjacent the target of the anode and extracting said oil from the end of the anode, a second source of oil supply, and means

- for connecting said second source in circulatory relation to the interior of the casing, said conduits being in part of insulating material exteriorly, protected against breaking down by said oil circulated through the interior of the casing.
3. In an X-ray apparatus, a casing, an X-ray tube therein including an anode, an external source of dielectric oil, conduits intermediate said source and the interior of the anode, said conduits passing through the casing and delivering said oil immediately adjacent the target and extracting the oil from the end of the anode, a second source of oil supply, and means for connecting said second source in circulatory relation to the interior of the casing, said conduits being in part of insulating material protected against breaking down by said oil circulated through the interior of the casing, and a filter for said second source of oil arranged beyond the casing.
- 20 4. In an X-ray apparatus, a casing, a cooling system external of said casing, an X-ray tube within the casing, circulating connections leading through the casing for directing dielectric oil for cooling and insulating the anode of the tube, said oil being maintained at ground potential, said circulating connections being in part of insulating material to prevent the high potential of the tube from charging the cooling system beyond the casing, said circulating connections being in flexible connection with the tube, whereby to permit independent movement of the tube under expansion and contraction without interfering with the oil circulation.
5. In an X-ray apparatus, a casing, an X-ray tube within the casing, circulating connections for directing a dielectric oil of ground potential to the anode of the tube, said circulating connections leading from a source beyond the casing to and through the casing and including sections of insulating material to prevent the high potential of the tube charging the cooling system beyond the casing, and means for independently circulating a cooling oil within the casing exteriorly of the tube, said latter cooling oil surrounding and externally insulating the insulating sections of the circulating connections.
6. In an X-ray apparatus, a casing, an X-ray tube within the casing, a conduit of insulating material flexibly connected to the tube for leading a dielectric oil into the anode of said X-ray tube, and means for providing for the discharge of the hot oil from the tube to and through the wall of the casing, said discharge means being in part of insulating material and preventing contact of the dielectric oil with the external or other portions of the walls of the X-ray tube.
7. In an X-ray apparatus, a casing, an X-ray tube within the casing and including an anode, means for circulating a dielectric oil from a point beyond the casing to and within the anode, said means including insulating sections carried by and rigid with the casing to insulate said tube for preventing leakage of the high potential of the anode, said insulating sections being flexibly connected to the tube.
8. In an X-ray apparatus a casing, an X-ray tube within the casing and including an anode, circulating connections for directing a dielectric oil from a source beyond the casing to and through the casing and to and within the anode, said connections including insulating parts to insulate the tube against high-potential leakage, and means for directing an independent circulation of a cooling agent within the casing externally
- of the X-ray tube and surrounding said insulating parts for external cooling and insulating thereof.
9. In an X-ray apparatus, a casing, an X-ray tube therein, insulated connector posts carried by the casing and supporting the tube, means for removably securing one end of the tube to one of said posts, a section removably carried by the other of said posts and formed with an opening, the cooperating end of the tube being formed with an extension corresponding in shape to that of the opening in the section and slidably fitting in said opening, said opening being without obstruction or resistance to the free movement of the cooperating end of the tube in both directions under expansion and contraction of the tube, and anti-friction means carried by the section and bearing on the tube extension fitting in the opening to facilitate movement of the tube under expansion and contraction.
10. In an X-ray apparatus, a casing, an X-ray tube therein, insulated connector posts carried by the casing and supporting the tube, means for removably fixing the cathode end of the tube to one of said posts, means for mounting the anode end of the tube for free axial movement of the tube under expansion and contraction, circulating connections for a dielectric oil opening within the anode of the tube, and flexible connections in said circulation connections to permit axial movement of the tube under expansion and contraction without interfering with oil circulation.
11. An X-ray apparatus including a casing, an X-ray tube therein, means for circulating a cooling fluid within the casing exteriorly of said tube, an anode in said tube, circulating connections for circulating a cooling fluid within the anode, said connections being in part of insulating material for insulating the anode cooling system exteriorly of the casing from the high anode potential, and said parts of insulating material being surrounded by the cooling fluid circulated in the casing for insulating and cooling said parts.
12. In an X-ray apparatus, a casing, a tube within the casing including an anode, means leading from a source beyond the casing for circulating dielectric oil to, within, and from the anode, said means having flexible connection with the tube and rigid connection with the casing, said means insulating the casing from the high potential of the tube.
13. In an X-ray apparatus, a casing, a tube therein including an anode, circulating tubes leading from a source of dielectric oil beyond the casing to and through the casing and to and from the anode, said tubes having flexible sections to permit independent expansion and contraction of the X-ray tube and insulating sections to prevent the high potential of the X-ray tube from charging the casing and parts of the circulatory system beyond the casing.
14. In an X-ray apparatus, a casing, an X-ray tube therein including an anode, a source of dielectric oil beyond the casing, tubes leading from said source through and being fixedly supported by the casing and to and within the anode for circulating the dielectric oil within the anode, said tubes in the lengths between the anode and casing being of insulating material and of flexible connection with the anode, whereby to insulate the casing and source of dielectric oil beyond the casing from the high potential of the anode.

DISCLAIMER
